US0D1058427S

(12) **United States Design Patent** (10) **Patent No.:** **US D1,058,427 S**
(45) **Date of Patent:** **** Jan. 21, 2025**

(54) **GEMSTONE**

(71) Applicant: **Kendra Scott, LLC**, Austin, TX (US)

(72) Inventors: **Leah Lucus**, Austin, TX (US); **Ramie Simonson**, Austin, TX (US)

(73) Assignee: **Kendra Scott, LLC**, Austin, TX (US)

(**) Term: **15 Years**

(21) Appl. No.: **29/960,636**

(22) Filed: **Aug. 30, 2024**

(51) LOC (15) Cl. **11-01**

(52) U.S. Cl.

USPC **D11/90**

(57) **CLAIM**

The ornamental design for a gemstone as shown and described.

DESCRIPTION

FIG. 1 is a top right front perspective view of a gemstone in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged partial view of FIG. 4.

The broken lines in the drawing depict the boundary of the enlarged view of the gemstone and form no part of the claimed design.

1 Claim, 5 Drawing Sheets
